DESIGN FOR A VENDING MACHINE

Arthur R. Constantine and Melvin H. Boldt, South Bend, Ind., assignors to Bendix Home Appliances, Inc., South Bend, Ind., a corporation of Delaware

Application August 7, 1944, Serial No. 114,761

Term of patent 14 years

(Cl. D52—3)

To all whom it may concern:

Be it known that we, Arthur R. Constantine and Melvin H. Boldt, citizens of the United States, residing in South Bend, in the county of St. Joseph and State of Indiana, have invented a new, original, and ornamental Design for a Vending Machine, for which the following is a specification, reference being had to the accompanying drawing, forming part thereof.

The figure is a perspective view of a vending machine showing our new design. The side of the device not shown is substantially identical with the side shown, the rear however being substantially plain.

We claim:

The ornamental design for a vending machine, as shown and described.

ARTHUR R. CONSTANTINE.
